UNITED STATES PATENT OFFICE

1,985,052

AIR COOLER AND CIRCULATOR

Arthur B. Modine, Racine, Wis., assignor to
 Modine Manufacturing Company, Racine, Wis.,
 a corporation of Wisconsin

Application June 25, 1932, Serial No. 619,221

9 Claims. (Cl. 62—133)

The invention relates to a device for cooling and circulating air and has as one of its principal objects the production of a device of this character which may be readily arranged at any 5 desired location in a room of a dwelling, office or hotel and which is neat and unobjectionable in appearance.

It is an object of the invention to provide a construction which may be readily varied as 10 to size and cooling capacity so as to compensate for rooms of various dimensions or the degree of temperature desired.

Another object of the invention is to provide a device capable of accomplishing the above 15 mentioned advantages, having an air advancing means combined therewith to thereby advance air through the device to cause said air to be cooled and be discharged from the device in a cooled condition.

20 In addition to the above, it is an object of the invention to provide a receptacle for a cooling medium, the receptacle having an air passage which engages the cooling medium, the receptacle having a closure, the closure having an air passage which communicates with the air 25 passage of said receptacle, the closure having air advancing means located therein and means for actuating the air advancing means carried by the closure.

30 It is an object of the invention to provide a construction such as that just referred to in which the member providing the closure may be removed from the member providing the receptacle so that a cooling medium may be introduced and be discharged therefrom when this 35 becomes necessary or desirable.

In addition to the above, it is an object to 40 provide means for receiving condensate occurring upon the outside of the receptacle, this last mentioned means being arranged relatively to certain air passages in the device so that condensate occurring in this last mentioned passage may also find its way to said means.

45 A further object of the invention is to provide certain air passages employed in the device with baffles so that the air circulating through said passages is directed toward the cooling medium prior to its discharge from the device.

50 It is another object of the invention to provide a device of the kind above referred to which may be conveniently arranged at a desired location in a room and which provides an air cooling and circulating unit having the out-

let thereof located at one end adjacent the upper portion thereof and the air inlet located adjacent the lower end, this last mentioned end having means whereby air to be cooled is introduced to the device.

The invention has these and other objects, all of which will be explained in detail and more readily understood when read in conjunction with the accompanying drawing which illustrates one embodiment of which the invention 10 is susceptible, it being manifest that changes and modifications may be resorted to without departing from the spirit of the appended claims forming a part hereof.

In the drawing, Fig. 1 is a central longitudinal section of a device constructed to accomplish the invention, the device being comprised of separable receptacles for the cooling medium to thereby increase or decrease the number thereof and vary the cooling capacity of 20 the device;

Fig. 2 is a top plan view partly in section; Fig. 3 is a section taken on line 3—3 of Fig. 1; and

Fig. 4 is a section taken on line 4—4 of Fig. 1. 25 The structure illustrated in the drawing contemplates the utilization of a casing 10 which is designed to be supported in a vertical position upon the end 11, having air advancing means generally designated 12 located at the opposite 30 or upper end of the device. An air advancing means is employed and located in an air passage generally designated 13, this passage has an outlet 14 which is preferably arranged to discharge cooled air in a lateral direction.

35 As before stated, it is an object of the invention to provide a device capable of readily having the cooling capacity thereof varied and to this end, the invention contemplates the provision of one or more separable receptacles respectively designated 15 and 16, the latter of which is mounted upon the former and arranged relatively to the former so that air may circulate through both of said receptacles and be discharged from the outlet 14. Each of these 40 receptacles 15 and 16 is open at one end as indicated at 17 and 18 respectively so that the closed end 19 of one of the receptacles such as 16 may be arranged relatively to the open end of the other to form a closure for the 45 latter, the open end 18 of the receptacle 16 being closed by the closure 20. This closure 20 is provided with the passage 13 and said closure supports an air advancing means generally designated 12 and a motor 21 for actu- 50 55

ating the air advancing means. Manifestly, should it be desired to reduce the capacity of the device, this may be accomplished by separating the receptacles from each other and applying the closure 20 to the end 17 of the receptacle 15, it being understood that should it be desired to increase the capacity of the device, the receptacle 16 will be applied to the end 17 of the receptacle 15 as illustrated in the drawing with the closure 20 arranged in the manner shown.

Each of the receptacles 15 and 16 is provided with an air passage designated respectively 22 and 23 which is arranged within the respective receptacles. These passages are open at their opposite ends to form a communication with said receptacles 15 and 16 and atmosphere. In the structure illustrated, the members forming the air passages 22 and 23 are of a relatively flat elongated cross section and extend from the bottom of each receptacle to near the top thereof. The members 22 and 23 providing the air passages are spaced from the walls of said receptacles and thus provide spaces 24 and 25 respectively which surround the air passages 22 and 23. These spaces 24 and 25 provide chambers in which cracked ice designated 26 may be arranged to provide the cooling medium.

Each of the elements forming the air passages 22 and 23 are provided with baffles 27, the baffles being arranged to direct the air drawn through the passages respectively designated 22 and 23 toward the cooling medium to thereby compel this air to engage the cooling medium prior to its being discharged from the device through the discharge opening 14. Each of the receptacles 15 and 16 is provided with handles 28 to facilitate separation and association of said receptacles during the filling or discharge thereof.

The end 11 of the receptacle 15 is maintained in spaced relation to the floor in which the device is located and to this end, a pan or receptacle 29 is employed to assist in forming a base for the device. This pan is provided with means for maintaining said end 11 in said spaced relation to said pan, this being accomplished through the agency of supports 30 which act as spacers which maintain the end 11 of the receptacle 15 in spaced relation to the annular wall of the receptacle or pan 29 and also maintain this end in spaced relation to the wall 31 of the receptacle or pan 29. This pan is provided to produce a catch for condensate occurring upon the outside of the receptacles 15 and 16 and also that condensate occurring within the air passage such as 22. It is evident that as condensate accumulates within the receptacle 29, it varies the space between the intake end of the passage 22 and the accumulated water and will thus vary the amount of air drawn into the passage 22 through the space provided between the annular wall 29 and the casing 15 and between the end wall of the casing 15 and the wall 31 of the receptacle 29.

The passage 13 formed in the closure 20 is provided with a chamber 32 in which the impeller 33 of the air advancing means generally designated 12 is located. This chamber has an opening 34 which communicates with the interior of the receptacles 15 and 16 and therefore as the impeller is actuated by the motor 21, air will be drawn through the space 35 provided between the annular wall 29 and the wall of the receptacle 15 and thence into the passage such as 22,

from which it is discharged into the receptacle 15. Upon travel of the air through the passage 22, said air will contact with the walls of said passage and become cooled by virtue of the fact that the passage is in contact with the cooling medium located in the chamber 15. This cooled air is caused to be directed by the baffles 27 toward the cooling medium prior to its introduction to the passage 23 of the receptacle 16. During the travel of the air through the passage 23, this air is again cooled by the cooling medium located in the receptacle 16, the cooled air being again caused to contact with the cooling medium in the chamber 16 by baffles similar to those designated 27 prior to its being withdrawn from the receptacle 16 by the impeller 33 of the air advancing means. The impeller causes the air to be circulated from the device and be discharged in a lateral direction through the opening 14 in the closure 20 and causes the air in the room to be circulated and drawn into the device to be again cooled.

From the foregoing description of the structure, it is manifest that a simple and effective construction is produced which will cause air to be circulated and cooled and discharged from the device in a lateral direction. It is further manifest that the elements entering into the construction of the device readily cooperate with each other to provide means whereby the cooling capacity may be increased or decreased depending upon the size of the room to be cooled or the degree of temperature desired to be maintained in the room and that the structure is of a portable character, neat in appearance and therefore will not be objectionable for use in high-class offices, homes and hotel rooms.

Having thus described the invention, what I claim as new and desire to cover by Letters Patent is:

1. In a device of the kind described, a base comprising a pan having bottom and vertical side walls, supporting members therein, a receptacle for containing a cooling medium, said receptacle being of lesser horizontal dimension than said pan and adapted to cooperate with said supporting members to maintain said receptacle in spaced relation above and inwardly with respect to the walls of said base, said receptacle having an opening in its bottom, a tubular member within said receptacle and contacting the cooling medium therein, said tubular member having one end connected to said opening and terminating at its opposite end near the top of said receptacle, a closure at the top of said receptacle having a passage therethrough, and means for maintaining a current of air through the several members of said device successively.

2. In a device of the kind described, a base comprising a pan having supporting members therein, a receptacle for containing a cooling medium and adapted to cooperate with said supporting members to maintain said receptacle in spaced relation above and inwardly with respect to the walls of said base, said receptacle having an opening in its bottom, a tubular member within said receptacle and contacting the cooling medium therein, said tubular member having one end connected to said opening and terminating at its opposite end near the top of said receptacle, means at the outlet of said tubular member for directing the air passing therethrough into direct contact with the cooling medium in said receptacle, a closure at the

top of said receptacle having a passage therethrough, and means for maintaining a current of air through the several members of said device successively.

5. 3. In a device of the kind described, a base comprising a pan having supporting members therein, a receptacle for containing a cooling medium and adapted to cooperate with said supporting members to maintain said receptacle in spaced relation inwardly with respect to the walls of said base, said receptacle having an opening in its bottom, a tubular member in contact with a substantial portion of the cooling medium in the receptacle and having one end 10 connected to said opening and terminating at its opposite end near the top of said receptacle, means at the outlet of said tubular member for producing turbulence in the fluid passing therethrough, a closure at the top of said receptacle having a passage therethrough and means for maintaining a current of air through the several members of said device successively.
15. 4. In a device of the kind described, a base comprising a pan having supporting members therein, a receptacle for containing a cooling medium and adapted to cooperate with said supporting members to maintain said receptacle in spaced relation to the walls of said pan, said receptacle having an opening in its bottom, a tubular member within said receptacle having one end connected to said opening and terminating at its opposite end near the top of said receptacle, a plurality of baffles at the outlet of 20 said tubular member for producing turbulence in the air passing therethrough and for directing said air into direct contact with the cooling medium in said receptacle, a closure at the top of said receptacle having a passage therethrough, and means for maintaining a current of air through the several members of said device successively.
25. 5. In a device of the kind described, a base comprising a pan having supporting members therein, a receptacle for containing a cooling medium and having a single side wall adapted to cooperate with said supporting members to maintain said receptacle in spaced relation inwardly with respect to the walls of said pan, said receptacle having an opening in its bottom, a tubular member within said receptacle and in contact throughout the greater portion of its length with the cooling medium contained in said receptacle, said tubular member having one end connected to said opening and terminating at its opposite end near the top of said receptacle, a second receptacle similar to said first mentioned receptacle and having a similar tubular member positioned therein removably mounted upon the upper end of said first mentioned receptacle adapted to operate as a continuation thereof, a closure at the top of said second receptacle having a passage therethrough, and means for maintaining a current of air through the several members of said device successively.
30. 6. In a device of the kind described, a base comprising a pan having supporting members therein, a receptacle for containing a cooling medium and adapted to cooperate with said supporting members to maintain said receptacle in spaced relation to the walls of said base, said receptacle having an opening in its bottom, a tubular member within said receptacle for producing turbulence in the fluid passing therethrough and for directing said fluid into direct contact with the cooling medium in the respective receptacles, a closure at the top of said second receptacle having a passage therethrough and means for maintaining a current of air through the several members of said device successively.
35. 7. In a device of the kind described a base comprising a pan having supports therein a receptacle for containing a cooling medium and adapted to cooperate with said supports to maintain said receptacle in spaced relation to the walls of said pan, said receptacle having an opening in its bottom, a tubular member within said receptacle and engageable throughout its entire length with the cooling medium contained in the receptacle, said member having one end connected to said opening and terminating at its opposite end near the top of said receptacle, a closure at the top of said receptacle having a passage therethrough, and means within said closure for maintaining a current of air through the several members of said device successively.
40. 8. In a device of the kind described, a base comprising a pan having supports therein, a receptacle for containing a cooling medium and adapted to cooperate with said supports to maintain said receptacle in spaced relation to the walls of said pan, said receptacle having an opening in its bottom, a tubular air conduit in said receptacle in direct contact with the cooling medium contained therein and having its receiving end connected to said opening and terminating at its discharge end near the top of said receptacle, a plurality of baffles above the discharge end of said conduit and extending in opposite directions with respect thereto for producing turbulence in the air passing through the conduit and for deflecting the air in opposite directions into direct contact with the cooling medium in the receptacle, a closure at the top of said receptacle having a passage therethrough, and means within said closure for maintaining a current of air through the several members of the device.
45. 9. In a device of the kind described, a base comprising a pan having supports therein, a receptacle for containing a cooling medium and adapted to cooperate with said supports to maintain said receptacle in spaced relation to the walls of said pan, said receptacle having an opening in its bottom, a tubular member within said receptacle in direct contact with the cooling medium therein and having its receiving end connected to said opening and terminating at its discharge end near the top of said receptacle, a second receptacle similar to said first mentioned receptacle and having a similar tubular member positioned therein removably mounted upon the upper end of said first mentioned receptacle and adapted to operate as a continuation thereof, a plurality of baffles mounted respectively on opposite walls of said tubular member in each receptacle and extending in opposite directions above and in spaced relation to the discharge end of

said members for producing turbulence in the fluid passing through the members and for directing said fluid in opposite directions into direct contact with the cooling medium in said

5 receptacles, a closure at the top of said receptacle having a passage therethrough, and means

within said closure comprising a rotatory impeller positioned in said passage for maintaining a current of air through the several members of said device successively.

5 ARTHUR B. MODINE.
